CLAIM

The ornamental design for a gear for speed reducer, as shown and described.

DESCRIPTION

FIG. 1 is a front and right perspective view of a gear for speed reducer, showing our new design.

FIG. 2 is a front and left perspective view thereof.

FIG. 3 is a front elevation view thereof.

FIG. 4 is a rear elevation view thereof.

FIG. 5 is a top plan view thereof.

FIG. 6 is a bottom plan view thereof.

FIG. 7 is a left side elevation view thereof.

FIG. 8 is a right side elevation view thereof.

FIG. 9 is a cross-sectional view taken along the line 9-9 in FIG. 5; and,

FIG. 10 is a cross-sectional view taken along the line 10-10 in FIG. 5.

The broken lines shown in the drawings illustrate portions of the gear for speed reducer that form no part of the claimed design.
